Term of patent 14 years

Int. Cl. D25—01

U.S. Cl. D13—1 R

The sole figure is a perspective view of an interlocking wall unit showing my new design, the side not shown being flat and unornamented.

The bottom and rear surfaces, insofar as shown, are essentially flat or planar throughout for mating with similar mating surfaces, and may contain recesses therein.

I claim:

The ornamental design for an interlocking wall unit, as shown and described.
